STORAGE CONTAINER FOR BUNDLE TIES OR THE LIKE

Paul Farkas, Elizabeth, N.J., assignor to Thomas & Betts
Corporation, Elizabeth, N.J.

Filed Aug. 19, 1971, Ser. No. 173,339

Term of patent 14 years

Int. Cl. D9—03

U.S. Cl. D9—184

FIG. 1

FIG. 2 ← 5

FIG. 3

FIG. 4

FIG. 5

FIG. 6

FIG. 1 is a front perspective view of a storage container for bundle ties or the like showing my new design;

FIG. 2 is a front elevational view, the rear being a mirror image of the front;

FIG. 3 is a right side elevational view, the left side elevational view being a mirror image thereof;

FIG. 4 is a top plan view, the bottom plan view being a mirror image thereof;

FIG. 5 is a sectional view taken on the line 5—5 of FIG. 2; and

FIG. 6 is a view similar to FIG. 3 but with the top cover removed.

I claim:

The ornamental design for a storage container for bundle ties or the like, substantially as shown and described.
